UNITED STATES PATENT OFFICE.

GEORGE W. BRONSON, OF AMSTERDAM, NEW YORK.

DESIGN FOR A WHISK-BROOM HOLDER.

SPECIFICATION forming part of Design No. 17,025, dated December 21, 1886.

Application filed November 16, 1886. Serial No. 219,100. Term of patent 3½ years.

To all whom it may concern:

Be it known that I, GEORGE W. BRONSON, a citizen of the United States, and a resident of Amsterdam, in the county of Montgomery and State of New York, have invented certain new and useful Improvements in Designs for Whisk-Broom Holders; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a front view. Fig. 2 is a vertical section.

My invention relates to designs for holding whisk-brooms; and it consists of a pocket in ornamental form, when viewed in elevation, of an open parasol.

The leading feature of my design consists of an ornamental face-piece, which represents an open parasol, and is provided on its back face with a pocket for holding a whisk-broom.

A designates the parasol, which is open and expanded. B designates the suspending-ribbon, and C is a projecting portion of the pocket, which is provided with the customary opening in its bottom, through which the whisk-broom handle projects when the broom is in place in the pocket.

Having described this invention, what I claim, and desire to secure by Letters Patent, is—

The design for a whisk-broom holder herein shown and described, the same consisting of the representation of a raised or expanded parasol and the projecting pocket, substantially as specified.

In testimony whereof I affix my signature in presence of two witnesses.

GEO. W. BRONSON.

Witnesses:

CHAS. S. NISBET,
MARTIN L. STOVER.
